UNITED STATES PATENT OFFICE.

FRANK O. HELLSTROM, OF BISMARCK, NORTH DAKOTA.

BUILDING-BLOCK MOLD.

1,312,631.

Specification of Letters Patent. Patented Aug. 12, 1919.

Application filed May 2, 1918. Serial No. 232,034.

To all whom it may concern:

Be it known that I, FRANK O. HELLSTROM, a citizen of the United States, and resident of Bismarck, county of Burleigh, and State of North Dakota, have invented certain Improvements in Building-Block Molds, of which the following is a description, reference being had to the accompanying drawings, forming a part thereof.

- 10 The object of the invention is to provide a building block and mold therefor whereby the inconveniences heretofore experienced in the formation and setting of building blocks, and particularly those designed for use in 15 the construction of silos may be overcome, whereby in the formation of the blocks in tiers or series (a plurality being molded at one time or in one operation) a substantial uniformity of dimensions, shape, weight and 20 density may be attained without the employment of skilled labor, and whereby in the setting of the blocks, thus formed, a satisfactory fitting, joining and anchoring of the same may be attained.
- 25 Further objects and advantages of the invention will appear in the course of the following description, it being understood that changes in form, proportions and details of construction may be resorted to, 30 within the scope of the appended claims, without departing from the spirit of the invention.

In the drawings:

Figure 1 is a plan view of a mold showing 35 one embodiment of the invention.

Fig. 2 is a longitudinal sectional view of the same.

Fig. 3 is a transverse sectional view taken in a plane adjacent to the surface of a 40 molded block, showing the same in elevation with a portion of a division plate in rear thereof.

Fig. 4 is a view in perspective of one of the division plates.

45 Fig. 5 is a similar view of one of the pallets with a reinforcing member fitted in operative position thereto.

Fig. 6 is a view in perspective of one of the molded blocks.

50 The mold embodies side walls 10, a series of division plates 11 of which the lateral edges are fitted in grooves or seats 12 in the

inner surfaces of the walls, said division plates spanning the interval between the side walls, and a series of pallets 13 which 55 close the spaces between the division plates at their bottom or lower edges and which are constructed, as hereinafter more fully explained, to removably or detachably support reinforcing members 14 which, projecting upwardly from the pallets, in the spaces between the division plates, are in the course of the molding of the blocks, embedded therein and subsequently are removed with the blocks for use as hereinafter 60 explained. Preferably the plates are provided with dependent elements 15 to rest upon a bottom board or wall 16 connecting the side walls at their lower edges and also with upstanding terminal lugs 17 which 70 obviously produce corresponding recesses in the lower edges of the molded block such as indicated at 18 in Figs. 2, 3 and 6. The pallet is also provided with sockets 19, preferably consisting of grooves in the outer 75 surfaces of the lugs 17 for the reception of the extremities 20 of the reinforcing element 14. Obviously when the block is molded by pouring the semi-liquid cement into the spaces between the division plates, the out- 80 flow from said spaces being prevented by the pallets, the body portions of these reinforcing members become embedded in the blocks, and the detachment of the blocks, after the cement has become set, involves the 85 removal of the reinforcing member therewith, and the detachment of same from the pallet.

Moreover each pallet is provided at one side with a lateral projecting ledge 21 90 bounded at its inner side by a shoulder 22, said ledge being adapted to receive the edge of the division plate at that side of the pallet, said plate bearing against the shoulder 22 whereby a substantial interlock is formed 95 between the division plate and the pallet, while at the opposite side the pallet has an abrupt or plane bearing surface 23 which bears against the surface of the division plate at that side, and holds it securely in 100 place on the supporting ledge of the adjoining pallet.

Also the pallet is provided with a longitudinal rib 24 which forms a corresponding

groove 25 in the lower edge of the molded block as shown clearly in Fig. 6, the extremities 20 of the reinforcing member projecting therefrom to form connecting and anchoring means as between adjoining blocks and adjacent elements of the structure of which the blocks form parts.

The members of the mold box, consisting of the side and bottom walls are held in their proper relative positions to maintain the division plates and pallets in their described relations by means of transverse base bars 26 having terminal shoulders 27, side bars 28 engaged at their lower ends with said shoulders on the base bars; provided above the upper edges of the side walls with kerfs 29, and transverse tie rods 30 engaged with said kerfs and headed as at 31 to bear against the outer surfaces of the side bars as shown clearly in Figs. 1, 2 and 3.

It is obvious that the division plates may be of any desired form or configuration, such as flat, curved or otherwise, to suit the proposed shape of the blocks to be formed therebetween, curved or bowed plates having been selected for illustration in Figs. 1 and 4, while the pallet shown in Fig. 5 is straight.

The terminal division plate forming the end of the mold or series of mold members may be held in place by any suitable means such as cross bars 32, anchored in any convenient manner, and as a further reinforcement for the division plates a longitudinal reach bar 33 may be employed and provided on its under side with spacers 34 in the grooves or intervals between which are fitted the upper edges of said plates.

It will be understood that after the mold has been set up as described, the cement or concrete mixture may be flowed into the spaces between the division plates and suitably tamped, if desired or necessary, in order to secure uniformity of compactness as well as of size and shape of the blocks.

In the use of the blocks in the building of a silo or other wall the terminals of the reinforcing members may be intertwined or linked with those of adjoining blocks, or otherwise disposed to serve as anchoring means for engagement with such other elements of the wall as may be employed as means for maintaining the parts in their proper relative positions. It is also understood that blocks with the construction described can be employed either in single series or in multiple series with intervening spaces to provide air chambers as a protection of the contents of the structure from frost and the like.

Having described the invention, what is claimed is:

1. A mold for building blocks having side walls, spaced division plates spanning the interval between said walls, and pallets closing, respectively, the spaces between the

division plates, and provided with means for detachably supporting a block reinforcing member.

2. A mold for building blocks having side walls, spaced division plates spanning the interval between said walls, and pallets closing, respectively, the spaces between the division plates, provided with sockets for the reception of the terminals of block reinforcing elements. 70

75 3. A mold for building blocks having side walls, spaced division plates spanning the interval between said walls, and pallets closing, respectively, the spaces between the division plates, and provided with terminal grooved projections forming sockets for the reception of the terminals of block reinforcing members. 80

4. A mold for building blocks having side walls, spaced division plates spanning the interval between said walls, and pallets closing, respectively, the space between the division plates, and provided with sockets, to hold wire, block-reinforcing elements disposed above the pallets between the division plates which have depending terminals fitted removably in said sockets. 85

5. A mold for building blocks having side walls, spaced division plates spanning the interval between said walls, and pallets closing, respectively, the spaces between the division plates, and provided with longitudinal ribs and terminal lugs, arranged between the planes of the division plates to form corresponding grooves and recesses in the molded blocks. 95

6. A mold for building blocks having side walls, spaced division plates spanning the interval between said walls, and pallets closing, respectively, the spaces between the division plates, and provided with shouldered ledges for respectively engaging the lower edges of the same. 105

7. A mold for building blocks having side walls, spaced division plates spanning the interval between said walls, and pallets closing, respectively, the spaces between the division plates, and each having at one side a shouldered ledge for supporting one of said plates and at the other side a plate abutting surface. 110

8. A mold for building blocks having side and bottom walls, spaced division plates spanning the interval between the side walls and fitted at their edges in grooves in the side walls, pallets seated upon the bottom walls and closing the spaces between the division plates, transverse base bars having shouldered extremities projecting beyond the side walls, side bars engaged at their lower ends with the shoulders of the base bars, and headed tie rods connected with the upper terminals of the side bars and removably fitted in seats therein. 120

125 9. A mold for building blocks having

side walls, spaced division plates seated at their side edges in said walls, pallets closing the bottoms of the spaces between said division plates and having seats for the 5 lower edges thereof, and a longitudinal reach bar having means for spacing and seating the upper edges of the plates.

This specification signed and witnessed this 12th day of Nov., 1917.
